(57) **CLAIM**

The ornamental design for a waffle maker, as shown and described.

DESCRIPTION

FIG. 1 is a perspective view of a waffle maker according to the present invention;

FIG. 2 is a front view of the waffle maker of FIG. 1;

FIG. 3 is a rear view of the waffle maker of FIG. 2;

FIG. 4 is a left side elevation view of the waffle maker of FIG. 1;

FIG. 5 is a right side elevation view of the waffle maker of FIG. 4; and,

FIG. 6 is a top view of the waffle maker of FIG. 1.

The portions of the waffle maker shown in broken lines are for illustration purposes only and form no part of the claimed design.
